Primary Examiner — T. Chase Nelson(74) *Attorney, Agent, or Firm* — Laubscher, Spendlove & Laubscher, P.C.(57) **CLAIM**

The ornamental design for a tap shoe outsole and heel, as shown and described.

DESCRIPTION

FIG. 1 is a front perspective view of a first embodiment of my design;

FIG. 2 is a front view thereof;

FIG. 3 is a rear view thereof;

FIG. 4 is a right side elevation view thereof;

FIG. 5 is a left side elevation view thereof;

FIG. 6 is a top plan view thereof;

FIG. 7 is a bottom plan view thereof;

FIG. 8 is a front perspective view of a second embodiment of my design;

FIG. 9 is a front view of the embodiment of FIG. 8;

FIG. 10 is a rear elevation view of the embodiment of FIG. 8;

FIG. 11 is a right side elevation view of the embodiment of FIG. 8;

FIG. 12 is a left side elevation view of the embodiment of FIG. 8;

FIG. 13 is a top plan view of the embodiment of FIG. 8; and, FIG. 14 is a bottom plan view of the embodiment of FIG. 8. The dashed lines shown in the drawings illustrate environmental structure that forms no part of the claimed design.
